UNITED STATES PATENT OFFICE.

JACOB PEITZER, OF BROOKLYN, NEW YORK.

SKELETON FORM FOR HEADPIECES OF FURS.

Application filed November 26, 1926. Serial No. 150,833.

This invention relates to skeleton forms on which to build the head pieces for furs which are attached to what are known as chokers in the fur trade.

5 The principal object of the invention is to provide a skeleton form which will give the head piece when finished a lifelike, natural and permanent shape.

Other objects will appear as the disclosure 10 progresses. The drawings are merely intended to indicate a possible embodiment of the invention. It is obvious that actual needs of manufacture may necessitate certain mechanical changes. It is therefore not 15 intended to limit the invention to the embodiment illustrated, but rather to define such limits in the appended claims.

For a more detailed understanding of the invention, attention is now called to the 20 drawings in which—

Figure 1 is a top plan view of the form.

Fig. 2 is a side view thereof.

Fig. 3 is a section on line 3—3 of Fig. 1.

Fig. 4 is a perspective view of the hinge 25 piece.

Fig. 5 is a fragmentary top view of a modification of the device.

Fig. 6 is a side view thereof.

Fig. 7 is a section on line 7—7 of Fig. 5. 30 Referring to the drawings in detail in which like reference characters denote like parts throughout the specification, numeral 1 represents the base or foundation of the form and 2 a cup, when covered with fur, 35 forms the head of the animal. This cup is preferably made from rubber, in order to make the head resilient and soft to the feel of the hand and to spring back to its normal position in the event of being flattened.

40 For holding the cup in place, a staple 3 is provided. The base of the staple is attached to the base 1 of the form, and the upright ends 4 are formed into hooks 5, which are embedded in the cup 2 and thereby hold 45 it in place.

As noted in Fig. 1, the front end 6 of the base is somewhat pointed. This portion when suitably covered, simulates the snout of the animal.

50 For reinforcing the base, a longitudinal rib 7 and a cross rib 8 is provided. These ribs are preferably made of cork to give a proper degree of softness to the finished product.

55 In Fig. 5 is shown a modification of the device showing the rib 9 made out of sheet

metal, the rib 10 as in the preferred form made from cork. As noticed in Figs. 6 and 7, another strengthening rib 11 is provided underneath the base 1, and is parallel to the 60 rib 9.

It will thus be seen that I have provided a skeleton form which is simple in construction and relatively cheap to manufacture, and when covered with a suitable material 65 the device will simulate the head of an animal. The rubber cup which forms the head of the animal will be soft to the touch and spring back to its normal position in the event of being flattened down. 70

Having thus described my invention, what I desire to secure by United States Letters Patent is:

1. In a device of the class described, a base, a projection of said base on which to form the snout of the animal, a resilient cup having a flattened portion at the front which forms the head of the animal, and means for attaching the said cup to the base of the structure, the said means consisting of a cross rib attached to said base adjacent the inside of the front wall of said cup, a staple attached to said base and having upright members provided with hooks embedded in said cup, the front of said cup being supported between the said cross member and the uprights of said staples. 75

2. In a device of the class described, in combination, a base, a projection of said base on which to form the snout of the animal, 80 a rubber hemispherical cup having a flattened portion at the front which forms the head of the animal, the front end of said cup supported by staples having a pair of prongs which are embedded in said cup and a cross member attached to said base and bearing against the inner front face of said cup. 85

3. In a device of the class described, in combination, a base, a projection of said base on which to form the snout of the animal, a rubber hemispherical cup having a flattened portion at the front which forms the head of the animal, means for fastening the front portion of said cup to the base, the rear portion being free, the said fastening means consisting of a staple having a base attached to the first-mentioned base, and arms projecting upward from said base having hooks at the ends for holding said cup 95 in place, and a cross member attached to said base for holding the front portion of the 100

110

- cup between said staple and cross member.
4. In a device of the class described, in combination, a base, a projection of said base on which to form the snout of the animal, a rubber hemispherical cup which forms the head of the animal, means for fastening the front portion of said cup to the base, the rear portion being free, the said fastening means consisting of a staple having a base attached to the first-mentioned base, and arms projecting upward from said
- 5
- base having hooks at the ends for holding said cup in place, a rib attached to the front part of said base forming the upper portion of the snout of the animal and another rib 15 at right angles to the first-mentioned rib and bearing against the inside of the front portion of the cup, the said cup supported between said uprights of the staple and last mentioned rib. 20

In testimony whereof I affix my signature.
JACOB PEITZER.
